CHARLES TURNER, OF AIRDRIE, SCOTLAND

CARBONIZING OR LIKE RETORT

Application filed March 21, 1928, Serial No. 263,349, and in Great Britain May 31, 1927.

A common device for discharging a vertical carbonizing or like retort which is being fed intermittently or continuously with coal or the like is an Archimedian screw revolving with its axis vertical in the lower part of the retort. Since the screw must be of such diameter that it substantially fills the cross section of the retort and the power required to turn it increases with its diameter, there is a limit to the cross sectional dimensions of a retort wherein the device is used, if consumption of power is of importance.

By my invention I use two or more Archimedian screws intermeshing with each other. When more than two are used there is an additional advantage in retorts into the lower part of which steam or gas is to be introduced, particularly when the steam or gas is superheated to supply the heat necessary for low temperature carbonization.

Various considerations lead to the desirability of introducing the steam by means of a pipe entering the retort in the region below the Archimedian screw and yet delivering the steam above the screw and without using the shaft of the screw as a passage.

By using four or more screws the shafts of which are symmetrically arranged in relation to the axis of the retort, there is obtained a space about the said axis in which the vertical portion of the steam pipe can be accommodated.

In the preferred construction there are five screws the shafts of which are supported in a spider extending across the retort. This spider also supports a vertical pipe closed at its upper end but suitably perforated for delivery of the steam. Into the contracted lower end of the pipe extends a second pipe making a substantially steam-tight joint with the contracted end and having a right angle bend. The horizontal portion of the bend forms a spigot and socket joint with a horizontal pipe entering the retort through a side thereof.

The use of the word axis is not intended to imply that the retort must necessarily be cylindrical.

Attention may be called to the fact that it is not always necessary to rotate the Archi-

median screws in order to produce the discharge. The material treated in the retort suffers a change of form or structure during the treatment so that its natural angle of repose is changed. Hence by suitable selection of the pitch of the screws the conditions may be such that while the material rests on the screws during the treatment, it automatically slides down the screws when its treatment is complete, the screws remaining stationary.

The accompanying drawings illustrate the application of five Archimedian screws in the manner described above.

Fig. 1 represents a vertical section through a retort embodying the invention, Fig. 2 being a view in horizontal section on the line 2-2 of Fig. 1.

The retort is particularly applicable to a process of low temperature carbonization in which the fuel is heated by introduction into the retort of superheated steam, the pressure being allowed to rise in the retort and then quickly released so that there are pulsations of pressure throughout the process. The retort *a* is surmounted by a hopper *b* from which the material to be heated, generally coal, is discharged into chamber *c* by intermittent opening of valve *d*. The opening of this valve alternates with that of valve *e* which admits coal into the retort.

In the lower end of the retort is mounted a spider *f* through which extend the vertical shafts *g* of the Archimedian screws. These shafts also extend through glands *h* forming part of the conical casting constituting the bottom of the retort. The shafts are driven by gearing, not shown, so as to rotate at the same speed in the same direction, indicated by arrows. This speed depends upon the character of the material which is being heated in the retort and in some cases, as already stated, may be reduced to zero.

Over a central opening in the spider is mounted a pipe *i* closed at its upper end and perforated as shown to permit issue of steam supplied through pipe *k* which forms a substantially steam-tight fit in the said opening.

The offtake *l* of the retort contains a valve *m* which is opened at intervals (by the action

of any known device depending upon the attainment of the desired pressure in the retort) to permit rapid escape of elastic fluid from the retort, and closes again when the pressure in the retort has fallen to the desired limit.

In a specific instance, a truncated conical cast iron retort is used in carbonizing cannel coal. It is 10 ft. in diameter and of height 10 suitable for a charge of 20 tons of the coal of size to pass a 4" mesh sieve. The diameter, length and pitch of each of the five screws are respectively 4 ft., 21 ins. and 14 ins. respectively.

15 The steam is superheated to 600° C. and is supplied at the rate of 150 lbs. per minute. The automatically operated valve *m* in the offtake at the top of the retort opens 4 times per minute and remains open 2 seconds on each occasion.

Under these conditions the screws are rotated only when the discharge of coke through the opening *n* into chamber *o* becomes irregular, showing a tendency for the charge to hang, since normally the coke slides down the screws at the desired rate.

The foregoing is only a specific instance. In other cases the screws require to be rotated continuously at the speed determined experimentally for the conditions attending the process.

The invention is also applicable to any process in which the temperature does not prohibit the use of the material of which the screws are constructed.

I claim:

1. A carbonizing vertical retort comprising a shell adapted for unimpeded descent of a charge of solid material through the upper part thereof, a hollow member of substantially inverted cone shape constituting the bottom of the retort, a plurality of vertical shafts extending through the said hollow member into the lower part of the shell, and 45 an Archimedian screw fixed to the upper part of each of the said shafts, said screws being adapted to together support and discharge a charge of solid material in the shell and each of them intermeshing with and adapted to 50 rotate at the same speed in the same direction as the adjacent screws.

2. A carbonizing vertical retort comprising a shell adapted for unimpeded descent of a charge of solid material through the upper part thereof, a conical hollow member constituting the bottom of the retort, at least four vertical shafts extending through the said hollow member into the lower part of the shell and arranged symmetrically around the axis 60 of the shell, an Archimedian screw fixed to the upper part of each of the said shafts, said screws being adapted to together support and discharge a charge of solid material in the shell and each of them intermeshing with and 65 adapted to rotate at the same speed in the

same direction as the adjacent screws, and a pipe extending upwardly into the shell coaxially with said shell and terminating above the upper ends of the said screws.

In testimony whereof I have signed my name to this specification.

CHARLES TURNER. [L. S.]
